UNITED STATES PATENT OFFICE

156,634

TIE CLIP OR SIMILAR ARTICLE

Irving M. Lang, New York, N. Y.

Application January 21, 1949, Serial No. 354

Term of patent 3½ years

(Cl. D17—10)

To all whom it may concern:

Be it known that I, Irving M. Lang, a citizen of the United States of America, residing in New York city, county of New York, and State of New York, have invented a new, original, and ornamental Design for a Tie Clip or Similar Article, of which the following is a specification, reference being had to the accompanying drawing, forming part thereof, wherein,

I claim:

The ornamental design for a tie clip or similar article, substantially as shown.

IRVING M. LANG.
